US0D1021362S

(12) **United States Design Patent** (10) Patent No.: **US D1,021,362 S**
(45) Date of Patent: ** Apr. 9, 2024

(54) **FOOTWEAR**

(71) Applicant: **ECCO Sko A/S**, Bredebro (DK)

(72) Inventor: **Ejnar Truelsen**, Tonder (DK)

(73) Assignee: **ECCO SKO A/S**, Bredebro (DK)

(**) Term: **15 Years**

(21) Appl. No.: **29/754,924**

(22) Filed: **Oct. 15, 2020**

Related U.S. Application Data

(63) Continuation of application No. 29/730,477, filed on Apr. 4, 2020, now Pat. No. Des. 933,342.

(51) **LOC (14) Cl.** **02-04**

(57) **CLAIM**

The ornamental design for footwear, as shown and described.

DESCRIPTION

FIG. 1 is a top, rear perspective view of footwear showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view.

The dot-dash lines illustrate the boundary of the claimed design and form no part thereof. The portions of the figures outside of the dot-dash line shown in lighter contrast illustrate the environment and form no part of the claimed design.

1 Claim, 7 Drawing Sheets
